VALVE CONSTRUCTION

Jesse D. Langdon, Long Beach, Calif.

Application November 25, 1944, Serial No. 565,129

9 Claims. (Cl. 137—592)

1

The instant invention pertains to valve construction whereby the component parts of the valve are chiefly constituted by the supply line of a liquid control valve with the objects in view of economical construction and manufacture together with silencing features constituted by means for changing the flow of liquid under pressure to a gravity flow.

Other and further objects and purposes will appear as the specification and operative description proceeds as illustrated by the drawings which show only one form of reduction to practice which may be changed within the scope of the claims.

Of the drawings:

Fig. 1 is a sectional view as at 1—1 of Fig. 2 showing supply tube S forming the inlet I, outlet slots OS with valve member open VMO, closed position shown by dotted lines VMC, operating lever OL and restricted inlet opening IO.

Fig. 2 is a top plan of which Fig. 1 is a sectional view.

Fig. 3 is a section as at 3—3, Fig. 2.

Fig. 4 is a separate top plan of pressure converter cup PC.

Fig. 5 is a separate sectional view of converter cup PC, showing gravity ports GP.

The instant invention consists of a supply tube S forming a liquid inlet I and having outlet slots OS cut for a distance downwardly from the upper end of tube S; a plug-like valve member in open position VMO inserted into said tube S, the slots OS being of greater length than said valve member VMO. The opposite walls of the slot OS form parallel extensions thru which the pivot pin P is inserted at the same time passing thru the operating lever OL which is thus held in position against the valve member VMO which is shown in open position in Fig. 1 leaving an open space between the operating lever OL and the bottom of the slot OS forming an outlet for liquid under pressure passing from the supply tube S beneath the valve member VMO and outwardly into the pressure converter cup PC which is enlarged to form a sump or cup of ample capacity to permit liquid to rise therein co-acting with gravity ports GP perforated thru an upwardly extended sleeve-like portion of the cup PC surrounding the tube S; the ports GP providing drain means for the cup PC. The gravity ports GP are preferably made triangular in form with a point of the triangle directed downwardly so as to permit any rise of liquid in the cup PC to flow therefrom at a proportionately faster rate as the liquid level in the cup PC rises. As the liquid level decreases the area of the ports GP decreases in proportion

2

to insure the projection of liquid at maximum velocity against the outer wall of the supply tube S down which the liquid passing from the cup PC runs by gravity. Stream director SD surrounds the ported tube S and directs liquid flowing from ports OS downwardly.

Special attention is called to the fact that a head of liquid rises in the chamber of cup PC to a point above outlet OS and serves to smother flow of liquid into the chamber and quiet the valve.

Any running liquid RL flowing down the outer wall of the supply tube S may be controlled by any shape of ports GP which may be desired to meet the conditions of liquid pressure flowing from the ports OS. However actual tests have proved that the restricted area formed by the downwardly projected apex of the ports GP forms a trough-like V-shaped outlet which projects liquid against the tube S with the greatest efficiency as the liquid level in the pressure converter cup PC diminishes due to the closure of the ports OS when the operating lever OL is depressed at its outer end the valve member is permitted to assume open position VMO. The closed position of the valve VMC, shown in Fig. 3, is assumed when the outer end of lever OL is raised.

A washer W is shown inserted in the supply tube S having the upper surface thereof disposed at a point substantially at the level of the valve member closing line VMC, the washer W has an inlet opening IO in the center thereof which may be proportioned to suit any condition of liquid pressure and control the rate of liquid flow with relation to the capacity of the cup PC and the area of the ports GP.

If it is desired to use the described valve as a ball-cock in a toilet flushing tank the device is installed with the outlet OS and the cup PC a suitable distance above any overflow outlet which is a conventional element in the construction of a toilet flushing tank to prevent backflow of liquid when subatmospheric condition of pressure exists within supply passage S of riser I. A float may be attached to the operating lever OL to control the opening and closing of the valve.

A suspending ring SR is formed above the ports GP of the cup PC and serves as means to support the cup PC when pressed over the outer circumference of the supply tube S.

It is preferable to have the valve member VMO formed of resilient material with a cup-shaped closure end, the concavity thereof facing the inlet opening IO and the outer edge thereof being sub-

ject to expansion against the inner wall of the supply tube S when subjected to liquid pressure.

It will be seen that the described device is a cross connection eliminator and therefore this application is a continuation in part of Ser. No. 389,436, filed April 19, 1941, and now abandoned.

Having described the invention and the operation thereof, the following claims are made:

1. A valve construction wherein a liquid supply tube forms the casing, said tube slotted to receive an operating lever pivotally disposed in said slot, said slot forming outlet means below the end of a piston-like valve member disposed in said tube when in open position, said valve member movable by the lever to close the outlet formed by the slot, a pressure converter cup surrounding said tube and the outlet means formed by the slot and supported by said tube, an opening thru the bottom of said cup adapted to hug said tube, ports adjacent the bottom of said cup and facing toward said tube whereby liquid under pressure projected from the slot into the cup will be projected by gravity through said ports against the outer wall of said tube to flow down same by gravity.

2. A valve as of claim 1 wherein the ports adjacent the bottom of said cup are triangular in shape with the apex thereof projecting downwardly.

3. A valve construction comprising a casing having an inlet, said casing being formed by a supply tube, a longitudinal slot dividing the end of the tube distal from a source of fluid pressure supply, a plunger reciprocally inserted in the slotted end of said tube and closing a portion of said slot, an operating lever inserted thru said slot and being pivotally held in operative position substantially transversely of and contacting said plunger, the end of said slot proximal to the source of fluid supply forming outlet port means, the portion of the lever contacting said plunger being eccentrically arranged with respect to the pivot and the opposite end of said lever extended beyond said pivot to an extent to provide a suitable leverage to actuate said plunger against fluid pressure within said tube and whereby the end of said plunger that faces the source of supply is permitted to clear the lower end of said slot and open the outlet port means, diverter means formed around said tube for pressure fluid flowing from said ports and being cuplike in form with the open end facing toward the supply end of said tube and having the closed end attached to said tube above the outlet ports formed by said slot, another larger cuplike member formed around said tube and facing the first named cuplike member and including outflow openings facing toward said supply tube whereby fluid under pressure passing from said ports will be diverted into the second cup by the first cup and will be permitted flow from the last to cup by gravity in a stream surrounding said supply tube.

4. A device as of claim 3 in which the lower edge of the first cuplike member extends downwardly to at least the upper confines of the outflow openings of said larger cuplike member.

5. In combination with a valve of the class described, an inverted cup attached to the valve head above port means forming outlet means for the valve, the wall of the cup surrounding said outlet means and projecting downwardly, the open end of said cup facing the bottom of a larger cup having the open end thereof projecting upwardly and facing in the opposite direction to the first named cup, the last named cup being provided with ports thru an upturned portion thereof surrounding and attached to a riser forming an inlet tube for said valve, whereby the first named cup diverts the flow of liquid into the second named cup from whence liquid flows by gravity downwardly around said riser.

6. A pressure converter cup for combination with a valve of the kind described, said cup having a bottom with a central portion extended upwardly of the bottom thereof and forming attaching means surrounding an inlet tube provided for said valve, said cup having the open end thereof facing upwardly, said bottom being below outlet means provided for said valve, said cup being adapted to receive a flow of liquid from said outlet means, outflow means from said cup perforated thru the upwardly extended portion thereof, whereby liquid is permitted to flow by gravity from said cup and form a stream flowing downwardly of and following said inlet tube.

7. A device as of claim 6 wherein the outflow means from the cup is formed by apertures facing the inlet tube, an imperforate annular shelf being formed by the bottom of the cup between the upturned surrounding portion of the cup forming the wall of an annular chamber whereby the head of liquid from the valve outlet is accumulated and rises above said outlet aiding to smoother and quiet flow of liquid into said cup.

8. A device as of claim 6 wherein the outflow means is formed by triangular apertures facing the inlet tube, an apex of the triangular aperture being pointed downwardly whereby flow of liquid from said apertures is concentrated and slowed down as the level of the liquid head in said cup is lowered by diminished delivery of liquid thru the valve outlet during closure of the valve.

9. A device as of claim 6 including a cuplike structure surrounding the outlet means of the valve, the open end of the cup facing downwardly whereby liquid is directed downwardly into the first named cup.
